ENVELOPE MACHINE

Ferdinand L. Smithe, New York, N. Y., assignor
to F. L. Smithe Machine Co., Inc., New York,
N. Y., a corporation of New York

Application August 12, 1932, Serial No. 628,494
Renewed August 22, 1935

7 Claims. (Cl. 93—62)

This invention relates to envelope machinery and more particularly to means for making window envelopes.

The invention has for an object to contrive a mechanism in combination with a standard envelope making machine, for taking whole blanks, cutting windows in them, applying window patches to the blanks and delivering them to the standard envelope machine.

10 A mechanism of this character has the advantage that there is no necessity for carrying stocks of blanks provided with windows because the same blanks may be used for producing envelopes with or without windows. It has the further advantage that the same standard machine may be employed for making envelopes with or without windows. Thus if envelopes with windows are wanted the blanks are put into a magazine and fed through the window cutting and patch applying mechanism to the supply magazine of the standard machine, whereas if envelopes without windows are wanted the blanks are put directly into the supply magazine of the standard machine and the window cutting and patch applying mechanism is caused to remain idle.

Other objects and advantages will hereinafter appear.

In the drawings forming part of this specification,

Figure 1 is a fragmentary, diagrammatic view in side elevation illustrating the window cutting and patch applying mechanism in conjunction with a fragment of a standard envelope making machine;

Figure 2 is a fragmentary, sectional, side elevation on a larger scale than Figure 1 showing a portion of the mechanism illustrated in Figure 1; and

Figure 3 is a fragmentary plan view of the mechanism of Figure 2, the table being omitted.

The envelope blanks are placed in the form of a stack 1 in a magazine 2. The blanks are taken singly from the bottom of the stack by separator mechanism. This separator mechanism is desirably the same as that illustrated in the pending application of Abraham Novick, Serial No. 628,302, filed August 11, 1932, for Envelope machines, and is, therefore, only partially illustrated herein. Briefly, the separator mechanism comprises a pneumatic picker device 3, Figure 2, which starts the lower edge of a blank away from the stack, a wedge or dagger device 4 which presses the separated margin away from the stack and toward a variable speed roller 5, and

auxiliary feed rollers 6 which are oscillated upon the periphery of the feed roller 5 to cause the lower margin of the blank to be gripped to and fed forward by the feed roller 5 at the appropriate time in the cycle. The feed rollers 5 and 6 start the blank along a table 7.

A feed roller 8 cooperates with the feed roller 5, through the table, to deliver the blank to a feeding couple comprising a lower roller 9 and an upper notched roller 10. The leading edge 10 of the blank passes the normal line of contact of the rollers 9 and 10 while the notches 10a are opposite the rollers 9. The rollers 9 and 10 are thus caused to come into gripping engagement with the blank at the leading edges of the side flaps so that slipping is avoided. The variable speed feed roller 5 is rotating at as great peripheral speed as the rollers 9 and 10 from the time when rollers 9 and 10 first grip the blank until the blank has passed from between the grip of the rollers 5 and 8.

The blank is delivered by the rollers 9 and 10 to a pair of rollers 11 and 12. The roller 12 is provided with a cutting die 13 for cutting a window opening in the blank and the roller 11 is provided with a suitable cutting bed or surface for co-action with the die 13. The die 13 leaves the blank chip adhering by a few fibers to the main body portion of the blank and the blank, with the chip still present, advances between feed rollers 14 and 15 to a chip removing mechanism 16.

The chip removing mechanism 16 comprises upper and lower rollers 17 and 18. The upper roller 17 carries a tucker blade 19, and the lower roller 18 carries a movable jaw 20. The blade 19 and the movable jaw 20 come into substantial registry at opposite sides of the blank simultaneously, and the tucker blade acts to tuck the blank chip which occupies the window space into the grip of the movable jaw. While the blank chip is thus displaced by the tucker blade, a tail portion 21 of the movable jaw 20 snaps abruptly off of a high portion of a stationary cam 22 and is urged to closed or gripping position as illustrated in Figure 2 by a spring 23 to securely grip the blank chip and carry it away. The advance of the blank is continued by a series of feed rollers 24 and cooperating feed rollers 25. It is delivered thence between a large feed roller 26 and cooperating feed rollers 27 and 28. The roller 28 diverts the blank upwardly and causes it to come into engagement with a feed drum 29. Pins 30 on the drum 29 come into engagement with the trailing edges of the side flaps of

the blank to carry it forward in definitely timed and aligned relationship to gumming mechanism 30 and patch applying mechanism 31. These mechanisms are generally like the corresponding mechanisms disclosed in Figure 5 of Serial No. 628,302, referred to above.

The gumming mechanism comprises a gum box 32, a gum take-up roller 33, a transfer segment 34, and a roller 35 which carries a gum applying segment 36.

The patch applying mechanism comprises a reel 37 which supplies a web 38 of transparent window patch material. The web 38 passes around a guide roller 39 and a roller 40 for taking up the web slack and passes thence to a feeding couple comprising rollers 41 and 42. These rollers are intermittently operated to advance the web at each actuation a distance corresponding to the height of the desired window patch. The web is advanced past a stationary blade 43 and is severed after it comes to rest by a movable cutting blade 44. A blade carrier 45 imparts oscillatory movement to the movable blade 44, the carrier 45 being controlled by a cam 46 and a spring 47. At the time of severance of the patch, the patch is gripped between a movable table 48 and an intermittently driven roller 49. The leading end of the patch becomes impaled upon pins 50 carried by a patch transfer segment 51. The transfer segment 51 applies the patch to the gummed blank. The patch applying segment 51 travels at the same peripheral speed as the cylinder 29 when applying the patch. The continued rotation of the cylinder carries the envelope blank downward past rollers 52 and 53 and causes it to be deposited on the top of a stack 54 in a magazine 55.

The blanks are taken singly from the bottom of the stack 54 by a separator mechanism 56 and are arranged in fanned-out relation upon a belt 57. The blanks pass around a drum 58 beneath a guide belt 59 and are delivered onto the surface of a cylinder 60. The cylinder 60 carries the blanks in fanned-out relation past a gummer 61 and delivers them to a drying conveyor 62. The magazine 55 and the mechanisms which follow it are desirably the same as the corresponding parts illustrated in Serial No. 628,302, above referred to, and need not, therefore, be described in detail. The parts from the magazine 55 on constitute parts of a standard envelope making machine whereby the manufacture of the blanks into finished envelopes is carried out.

I have described what I believe to be the best embodiment of my invention. I do not wish, however, to be confined to the embodiment shown, but what I desire to cover by Letters Patent is set forth in the appended claims.

I claim:

1. The method herein described which consists in feeding blanks from a stack so as to com-

pletely individualize them, cutting window openings in the blanks, applying a window patch to each blank and arranging the blanks in fanned-out relation for further operation thereon.

2. In an envelope machine, in combination, means for taking envelope blanks successively from a stack so as to individualize the blanks, means for cutting window openings in the blanks, means for applying patches to the window openings, and means for arranging the blanks in fanned out formation for further operation thereon.

3. The method herein described which consists in feeding blanks from a stack so as to individualize them sufficiently to expose the window area of the blanks, cutting window openings in the blanks, applying a window patch to each blank and then arranging the blanks in overlapping relation with each other for further operation thereon.

4. In an envelope machine, in combination, means for taking envelope blanks successively from a stack so as to individualize the blanks, rotary means for cutting window openings in the blanks, rotary means for applying patches to the window openings, and means for arranging the blanks in overlapping formation for further operation thereon.

5. In an envelope machine, in combination, means for taking envelope blanks successively from a stack so as to individualize the blanks, rotary means for cutting window openings in the blanks, rotary means for applying patches to the window openings, means for gathering the blanks, and means for arranging the blanks in overlapping formation for further operation thereon, said last-named means comprising a support, means for gathering the blanks into a pile on said support and means for removing the blanks one at a time from said pile.

6. In an envelope machine, in combination, means for taking envelope blanks successively from a stack so as to individualize the blanks, rotary means for cutting window openings in the blanks, rotary means for applying patches to the window openings, means for gathering the blanks, and means for arranging the blanks in overlapping formation for further operation thereon, said patch applying means comprising a cylinder, means on the cylinder for conveying blanks, and means for gumming the window opening and applying the patch while so conveyed.

7. In an envelope machine, in combination, means for feeding blanks from a stack so as to individualize them sufficiently to expose the window area of the blanks, means to cut window openings in the blanks, means to apply a window patch to each blank and means to arrange the blanks in overlapping relation.

FERDINAND L. SMITHE.
